UNITED STATES PATENT OFFICE.

FREDERICK J. LINDENSCHMIDT, OF MILWAUKEE, WISCONSIN.

URETHRAL IRRIGATOR AND DILATOR.

SPECIFICATION forming part of Letters Patent No. 414,981, dated November 12, 1889.

Application filed July 24, 1889. Serial No. 318,486. (No model.)

To all whom it may concern:

Be it known that I, FREDERICK J. LINDEN-SCHMIDT, of Milwaukee, in the county of Milwaukee, and in the State of Wisconsin, have 5 invented certain new and useful Improvements in Urethral Irrigating and Dilating Devices; and I do hereby declare that the following is a full, clear, and exact description thereof.

10 My invention relates to urethral irrigating and dilating devices; and it consists in certain peculiarities of construction, as will be fully set forth hereinafter and subsequently claimed.

15 In the drawings, Figure 1 is a partly section plan view of my device. Fig. 2 is a plan view thereof. Figs. 3 and 4 are detail cross-sections on the lines 3 3 and 4 4, respectively, of Fig. 1. Fig. 5 is a detail section of a sleeve. 20 Fig. 6 is a detail section of part of a cannula, showing a curved end; and Fig. 7 is a detail section of a curved sleeve.

A represents a cannula, made, preferably, of brass and nickel-plated, the cannula shown 25 in Figs. 1 and 2 being straight, and having screw-threads formed on each end, as shown at a and b, the latter end receiving a cannula-cap B, with corresponding screw-threads, and having a tapered bore, as shown, of ordinary 30 construction.

C is the dilator, having internal screw-threads c d at each end, the former to fit upon the reduced screw-threaded end a of the cannula and the latter to fit upon the reduced 35 screw-threaded end e of the shank E of the irrigator F. The dilator has a series of longitudinal external convex ribs D D, forming grooves or channels f f between them. The irrigator F is of the general conical shape 40 shown, terminating in a knob or rounded tip G, and having a bore g extending only part through, of the same diameter as the bore h of the dilator and bore i of the cannula, there being one or more series of rearwardly-extending 45 passages j j j extending from said bore g to the outside of the irrigator.

The operation of my device will be readily understood from the foregoing description of its construction in connection with the accompanying drawings.

Figs. 1 and 2 illustrate the arrangement employed for dilating and irrigation at the same time. The instrument is inserted the required length in the urethra to reach the seat of the disease, and then the solution to 55 be injected is applied by inserting the tip or cap of an ordinary bulb or fountain syringe within the tapered bore of the cannula-cap B, and owing to the dilation of the urethral canal the said fluid which escapes through 60 the passages j makes its way out through the channels or grooves f f and over the outside of the instrument. In case dilation is not necessary, the dilator C may be removed and the irrigator and cannula connected by means 65 of a sleeve H. (Shown in Fig. 5.)

If the neck of the bladder is to be irrigated, a curved sleeve I, Fig. 7, is connected to the cannula (a cannula with a curved or elbow end k being preferably employed) and the 70 irrigator attached to this sleeve as before; but if only the membranous part of the urethra is to be irrigated the said curved sleeve I may be attached to a straight cannula and the irrigator attached to said curved sleeve 75 as before. In case of stricture it might be necessary to dilate these parts, and if so the dilator may be attached to the curved end k of the cannula.

It will be understood that the views in the 80 drawings are greatly exaggerated for the sake of clearness, the ordinary size of the cannula being three-eighths of an inch in its external diameter and the preferred size of the other parts being in the same proportion, though I 85 usually fit up a case with a series of different-sized dilators and irrigators, all designed to be attached to the same-sized cannulas.

Having thus described my invention, what I claim as new, and desire to secure by Letters 90 Patent, is—

1. The combination, with a cannula and irrigator, of a channelled dilator of greater diameter than said cannula interposed between the said parts and having a bore in communication with the bores in said cannula and irrigator, substantially as set forth.

2. The combination, with a cannula, of a dilator secured thereto, having a bore in communication with the cannula-bore and exte- 100

rior convex ribs forming grooves or channels between them, and an irrigator secured to the end of said dilator, substantially as set forth.

- 5 3. The combination, with a cannula having a cap provided with a tapered bore at one end and a dilator secured to the other end provided with exterior convex ribs forming grooves or channels between them, of a conical irrigator 10 having a reduced shank at one end secured to the adjacent end of the dilator and terminating in a knob or rounded tip, the said parts having communicating bores extending from

the cannula-cap to some distance within the irrigator, and oblique passages extending 15 backward from the bore within the irrigator to the outside of the rear portion thereof, substantially as set forth.

In testimony that I claim the foregoing I have hereunto set my hand, at Milwaukee, in 20 the county of Milwaukee and State of Wisconsin, in the presence of two witnesses.

FREDERICK J. LINDENSCHMIDT.
